UNITED STATES PATENT OFFICE

2,563,272

VENTILATOR

Max Rachlin, Flushing, N. Y.

Application June 18, 1948, Serial No. 33,891

5 Claims. (Cl. 98—71)

1

This invention is directed to a ventilator adapted to be placed upon a chimney or flue that extends through the roof of a building.

It is an object of the invention to provide a ventilator of rugged construction and one that is inexpensive to manufacture, involving relatively few parts.

It is a particular object to provide a ventilator which will rotate quite freely, even in the absence of a strong wind.

A more detailed object of the invention is to provide a ventilator having a one-piece hood formed with a body of substantially conical form and having an integral wind vane extending thereabove.

A further object of the invention is to provide a bracket of such form that it may be attached to the hood at three spaced points so as to support the hood securely and in such manner that it will rotate freely.

A detailed object of the invention is to provide a spindle which is anchored at its lower portion in such a manner that the spindle is permanently maintained upon a vertical axis or, stated in other words, the spindle and its base support are provided with definite means preventing wobbling thereof, such means insuring permanent stability of the spindle in a predetermined axial path.

Another object of the invention is to provide a ventilator made of fewer parts than ventilators heretofore manufactured, one form of the present ventilator being made from five pieces.

Another object of the invention is to provide a ventilator with a hood, this hood being formed by a relatively few simple bending operations, and in such manner that the vane is provided during the course of the bending operations.

To the accomplishment of the foregoing and related ends, said invention, then, consists of the means hereinafter fully described and particularly pointed out in the claims.

The annexed drawing and the following description set forth in detail one method and one product exemplifying my invention, such disclosed procedure and product constituting, however, but one of various applications of the principle of my invention.

In said annexed drawing:

Figure 1 is a partial central vertical section;

Figure 2 is a horizontal section on line 2—2;

Figure 3 is an elevation, looking from the right as viewed in Figure 1;

Figure 4 is an exploded view of the entire assembly of a modification of the ventilator as shown in Figures 1 to 3;

2

Figure 5 is an elevation of the modified form.

Referring now to the drawings, and particularly Figs. 1 to 3, inclusive, it will be noted that I have provided a hood 1 which is substantially 5 conical in shape and is provided with the usual opening formed by the edges 2 and 3. The lower portion of the hood is provided with a roll bead 4 to lend strength and rigidity to the hood structure and the upper portion is flattened to form 10 a wind vane, generally indicated at 5, the vane comprising two portions 6 and 7. These portions 6 and 7 are secured together by means of rivets 8, 9 and 10, thus maintaining the vane in a straight plane and also serving to strengthen 15 the body portion of the hood.

The hood is supported by means of a bracket of a very particular configuration. This bracket comprises a lower angularly extending part 15 which merges into a horizontal arm 16, this horizontal arm being apertured to receive the spindle 17. The arm 16 then extends upwardly, being connected to the intermediate horizontally extending arm 19 by means of the vertical portion 18. The arm 19 is apertured similar to the arm 20 and merges into the angularly extending portion 20, which in turn merges into the upper horizontal arm 21. The upper horizontal arm is provided with a depression 22 in its lower surface so as to receive the pointed end 23 of the spindle 17. The bracket terminates in a vertically extending portion 24, the terminal part of which is twisted to form a flat lug 25 that is received between the portions 6 and 7 of the wind vane 5. The rivet 9 serves to secure the bracket to the 25 upper part of the hood and at the same time secures the portions 6 and 7 together to form the wind vane.

The angularly extending portion 20 of the bracket is secured to the hood by means of bolt 30 or any other securing means. Similarly the bolt 31 secures the lower angularly extending flange 16 to the hood 1. A key 32 surrounds the spindle 17 to prevent upward movement of the bracket and assembled hood with respect to the spindle.

The spindle 17 is supported in such manner that wobbling or loosening is definitely prevented. This spindle is flattened to provide the lower base 33 and the flattened portion of the lower end of the spindle is pressed or otherwise deformed to provide a projection 34 which is preferably square in vertical section. The base 33 with its projection 34 is received between two cross bars 35 and 36, the cross bar 36 being provided with a recess in which the projection 34 is received. As a consequence of forming the recess, a projection

37 is formed on the cross bar 36. The base 33 and the cross bars 35 and 36 are secured together in any desired manner, for example by a rivet 38. The ends of the cross bars are provided with flanges 39, 40, 41 and 42. These flanges are adapted to be secured to ring 50 which in turn may be secured to a chimney or flue member in the usual manner.

Referring now to the modification shown in Figures 4 and 6, inclusive, it will be noted that this construction is somewhat similar to the preferred form shown in Figures 1 and 2, inasmuch as in this construction there are only five parts, including an attaching collar, whereas the preferred form involves six parts if a collar is attached to the flanges 39, 40, 41 and 42. The hood 50 of the modified form is slightly different in shape, although it may be said to be of generally conform configuration with an integral wind vane 51 rising from the top thereof. This vane 20 is formed by the upper portions 52 and 53, but in this form of the invention these portions are not secured together along the base lines 54 and 55.

The hood 50 is secured to the bracket generally indicated at 56 by means of the bolts 57 and 58, 25 it being noted that only two bolts are required, thus rendering assembly less difficult than is usually the case.

The bracket 56 comprises an upper horizontal arm 57, an angularly extending portion 58 which contacts the interior of the hood, and a lower horizontal arm 59. The upper end of the spindle is enlarged to provide the portion 60 so as to prevent upward movement of the bracket with respect to the spindle 61. Keys 62 and 63 are also provided to lend strength to the lower horizontal arm mounting the key 63, also preventing downward movement of the bracket 56 with respect to the spindle. The lower end of the spindle 61 is threaded at 62 so as to receive the bolt 63 which, as shown in Figure 7, is fastened below the cross bar 64. Any number of washers may be placed on the portion 62 and above the cross bar 64 so as to regulate the height of the hood with respect to the cross bar. The cross bar 64 is attached to the collar 65 and the collar 65 is attached to a chimney or other outlet in the usual manner.

From the foregoing it will be seen that I have provided a ventilator which in one form is provided with a relatively simple bracket but at the same time the hood and bracket structure are of such configuration that the entire assembly is extremely well-balanced. It will also be noted that the bracket is a three-point suspension, thus providing extreme durability and quiet operation, even in the event of high winds. It will be further noted that in preferred forms Figures 1 to 3, the spindle is permanently mounted in such manner that it will not wobble nor get out of alignment, or, stated in other words, it will remain in its original vertical axial position throughout the life of the ventilator.

As for the modification, this form is somewhat less expensive, but almost as durable as the preferred form. In this case, only five pieces are necessary, exclusive of the bolts, to make the entire ventilator. The ventilator of this modification is well-balanced and is obviously inexpensive, since the hood is formed entirely of one piece and is provided with a wind vane even though it is all of one piece.

Other forms may be employed embodying the features of my invention instead of the one here

explained, change being made in the form or construction, provided the elements stated by any of the following claims or the equivalent of such stated elements be employed, whether produced by my preferred method or by others embodying steps equivalent to those stated in the following claims.

I therefore particularly point out and distinctly claim as my invention:

1. A ventilator comprising a hood, a vertical spindle, a bearing bracket and two horizontally extending cross bars, said bearing bracket comprising a continuous strip, having two horizontal arms with apertures therein through which said spindle extends and having a third horizontal arm engaging the upper end of said vertical spindle, the lower end of said vertical spindle being flattened to provide a lower base portion, said base portion having a projection thereon extending out of the plane of said base portion and being received between said horizontally extending cross bars, one of said cross bars having a depression therein, said projection being seated in said depression and securing means extending through said cross bars and projection.

2. A ventilator as set forth in claim 1 wherein said projection and depression are square in vertical section.

3. A ventilator comprising a hood, a vertical spindle and a bearing bracket, said hood having the upper portions thereof flattened to form a wind vane, said bracket comprising a continuous strip and including a lower horizontal arm, an intermediate horizontal arm and an upper horizontal arm, the lower arm terminating in an angularly extending flange with securing means extending through the same and said hood, the upper horizontal arm terminating in a vertical leg, the upper end of said vertical leg being twisted at right angles to the plane of said vertical leg to form a flat lug, said lug being received between the flattened portions of said hood, and securing means extending through said lug and said hood portions.

4. A ventilator as set forth in claim 3 wherein said upper and intermediate arms are joined by an angularly extending portion and wherein securing means extend through said last-named portion and said hood.

5. A ventilator as set forth in claim 4 wherein the first-named securing means is located adjacent the lower edge of said hood and wherein the second-named securing means is located on the lower edge of said vane and approximately centrally thereof and wherein the last named securing means is located substantially intermediate of the other two.

MAX RACHLIN.
